CARBURETOR ACCELERATING PUMP

Milton A. Trisler, Birmingham, Mich., assignor to
General Motors Corporation, Detroit, Mich., a
corporation of Delaware

Application June 17, 1940, Serial No. 340,878

1 Claim. (Cl. 261—34)

This invention relates to means associated with a carburetor of the internal combustion engine type for providing temporary enrichment of the charge upon sudden increase in the demand for explosive mixture. In modern carburetor practice such devices usually include a liquid forcing device or "pump" actuatable in response to opening movement of the throttle valve to supply liquid fuel directly to the mixing chamber in excess of the amount that would be supplied by the suction normally operative at the carburetor jet or jets. Thus additional fuel is provided to take care of suddenly increased demand of the engine under accelerating conditions.

It is common practice to connect the so-called "accelerating pump" to the throttle valve actuating means in such manner that the pump delivers to the mixing chamber a definite or predetermined quantity of liquid for each opening movement of the throttle through a given range. It has been found, however, that the discharge from the pump should be graduated somewhat in accordance with the rapidity of opening movement of the throttle and particularly that, if the liquid forcing device is actuated to the same extent by a very abrupt opening of the throttle as it is by a slower throttle opening, the delivery of fuel upon the more abrupt movement is unnecessarily and detrimentally excessive.

The primary object of my invention therefore is to provide an accelerating device in which the delivery of the accelerating charge is graduated in accordance with the rate of opening movement of the throttle valve, less fuel being discharged when the throttle is suddenly opened than when the opening movement is slower. Further objects and advantages will appear from the following description taken in connection with the accompanying drawing in which

Figure 1 is an elevation of a carburetor showing means for actuating a fuel discharge device from the throttle valve, and

Figure 2 is a sectional elevation showing in detail a fuel discharge device embodying the present invention.

Referring to the drawing, 5 indicates a carburetor body which may be of any equal or suitable form including a mixing chamber 6, one or more venturis 7, 8, and means for delivering fuel thereto, such as a jet 9 from which fuel is discharged by reason of the suction exerted at the jet opening. A throttle valve 10 serves in the usual manner to control the flow of mixture from the mixing chamber to the engine, the carburetor being illustrated as of the downdraft type. A

float bowl is indicated at 11 and a conventional float at 12 whereby liquid fuel is maintained in the bowl or reservoir at a predetermined level as indicated at 13.

Associated with the reservoir 11 is an auxiliary fuel chamber 14 to which fuel may be conducted from the reservoir 11 through passage 15. A check valve 16 permits flow to the auxiliary chamber but prevents flow in the opposite direction. The auxiliary chamber is connected through outlet 17, check valve 18, and passage 19 to the "accelerating jet" 20 through which liquid fuel forced out of chamber 14 is discharged into the mixing chamber.

The chamber 14 has associated therewith a piston or plunger 21 operative upon outward movement to increase, and upon inward movement to decrease the volume of the chamber. This plunger may be sealed by the usual packing 22 of flexible material expanded by a spring ring 23 and retained by a perforated cap 24. The plunger is provided with an internal passage 25 having a valve seat 26 and communicating through the aperture 27 with the interior of the reservoir 11. A valve 28 held upon the seat 26 by spring 29 serves normally to close the passage 25 during inward movement of the plunger. Normally, therefore, when the plunger is moved outwardly liquid will be drawn into the chamber 14 from the reservoir 11 and when the plunger is moved inwardly liquid contained therein will be discharged through the jet 20.

To effect movement of the plunger, I have shown a U-shaped rod 30 one end of which is connected by link 31 to an arm 32 on the throttle shaft. The other end of the rod is slotted at 33 and is slidably fitted in the bore 34 of an extension 35 of plunger 21. A pin 36 passing through slot 33 limits movement of rod 30 relative to plunger 21. The valve 28 is provided with an extension 37 arranged in the path of movement of rod 30 in such manner that as the rod nears the inward limit of its movement relative to plunger 21 the end of the rod contacts the valve extension 37 and thereby opens the valve. A portion of the liquid then under pressure contained in chamber 14 may thereupon escape through cap 24, passage 25, and aperture 27 to the reservoir 11, the quantity thus being bypassed being determined, of course, by the pressure upon the liquid and by the size of the passages and the extent of opening of the valve 28.

A spring 38 is arranged between the plunger 21 and a collar or abutment 39 fixedly secured to rod 30. This spring provides resilient connec-

tion between the rod and the plunger, the strength of the spring being so selected that, during opening movement of the throttle up to a certain predetermined rate, the plunger will be forced inwardly by the action of the rod upon the spring and without permitting movement of the rod relatively to the plunger sufficiently to actuate valve 28. When, however, this rate of movement of the throttle is exceeded, the resistance to discharge from chamber 14 increases, the spring 38 is correspondingly stressed, and movement of rod 30 in bore 34 occurs sufficiently to effect opening of valve 28 and thus permitting the bypassing of a portion of the liquid in chamber 14 back to the reservoir or other source of supply. 15

It will be seen, therefore, that I have provided means for graduating the accelerating charge in accordance with the rate of increase in the demands of the engine. While the connection of the variable fuel discharge mechanism directly to the throttle valve constitutes a simple and convenient means for actuating the discharge mechanism, it will be understood that other actuating means as well as other changes in details of con- 20

struction may be utilized, depending upon the particular type and structure of carburetor employed.

I claim:

An accelerator pump for carburetors comprising the combination with a carburetor having a throttle valve, a mixing chamber and a fuel reservoir of a pump chamber whose intake communicates with said reservoir and whose outlet communicates with said mixing chamber, a plunger in said pump chamber having a bypass passage therein leading from said pump chamber to said reservoir, a valve carried by said plunger and controlling flow through said passage, an actuator operable in response to movement of said throttle valve and connected to said plunger by means permitting limited relative movement between said parts and resilient means tending to restrain such movement as the plunger moves inwardly, an extension on said bypass valve terminating near the actuator whereby the bypass valve is actuated by contact between the actuator and the extension upon occurrence of such movement to a predetermined extent. 25
